WRENCH

Charles E. Schilling, Willcox, Ariz.

Application December 26, 1940, Serial No. 371,743

2 Claims. (Cl. 81—102)

This invention relates to wrenches and an object of the invention is to improve generally upon such types of wrenches as are commonly known as "monkey wrenches"; and particularly improve upon the means for securing the sliding or adjustable jaw of the wrench in set position.

The invention together with its objects and advantages will be best understood from a study of the following description taken in connection with the accompanying drawings wherein:

Figure 1 is a side elevational view of a wrench embodying the features of the present invention.

Figure 2 is an edge elevational view thereof.

Figure 3 is an enlarged view taken substantially on the line 3—3 of Figure 2 and showing the parts positioned for freezing the shank of the movable jaw.

Figure 4 is a view similar to Figure 3 but showing the parts in set position.

Figure 5 is a detail sectional view taken substantially on the line 5—5 of Figure 1.

Figure 6 is a detail sectional view taken substantially on the line 6—6 of Figure 1.

Referring more in detail to the drawings it will be seen that the wrench embodies a jaw 5 formed integrally with one end of a shank 6 that in turn is formed integrally with one end of a handle 7.

Complementing the jaw 5 is a jaw 8 provided on one end of an integral shank 9.

The shank 9 works through a sleeve 10 provided therefor.

The sleeve 10 adjacent one end thereof is provided with a pair of ears 11 through the medium of which and a rivet or other pivot element 12 the sleeve 10 is pivoted to the shank 6 adjacent the jaw-equipped end of said shank.

At a relatively opposite end thereof the sleeve 10 is provided with a pair of coextensive guide arms 13 that straddle the shank 6 and at their free ends are connected by a cross web 14 that abuts the shank 6 to limit swinging movement of the sleeve 10 on its pivot 12 away from the shank 6.

The shank 9 is provided on one edge thereof with a longitudinal rack 15 with which is co-operable a locking pin 16 for holding the jaw 8 in the desired position of adjustment relative to the jaw 5.

The pin 16 is disposed between and has its respective opposite ends integral with or otherwise made fast to a pair of opposed carrier plates 17 that are accommodated in ways or grooves 18

provided internally of the sleeve 10 and on opposed walls of said sleeve.

At the ends thereof remote from the locking pin 16, the carrier plates are connected by a cross member 19 to which is anchored one end of a coil spring 20. The other end of the spring 20 seats in a recess 21 provided therefor in a wall of the sleeve 10 confronting the shank 6; it being noted, in this connection, that the sleeve 10 is provided with through openings 22 and 23 to permit free sliding movement of the carrier bars or plates 17 to permit shifting of the pin 16 into and out of engagement with the teeth of the rack 15.

From the description of the invention thus far it will be seen that normally the spring 20 urges the carrier bars 17 in a direction to engage the locking pin 16 with a tooth of the rack bar 15 for holding the shank 9 against axial movement through the sleeve 10, and consequently the jaw 8 in adjusted position relative to the jaw 5.

When the jaws 5 and 8 are engaged with the work the sleeve 10 is retained in the outward position with respect to the shank 6, as shown in Figure 4, through the medium of a thumb slide 24 against which the pin 19 will abut upon tendency of the sleeve 10 to swing toward the shank 6. The thumb slide 24 thus prevents the pin 19 coming into contact with the shank 6 as would result, as hereinafter explained in the shifting of the pin 16 out of engagement with the rack 15.

Relative to the statement last above made, it will be apparent that when it is desired to free the shank 9 for effecting a shifting of the jaw 8, sleeve 10 is swung inwardly toward the shank 6 so that the pin 19 engages an edge of the shank 6 in a manner to act on the pin 19 against the expansive action of the spring 20 for urging the pin 16 toward the right in Figure 5 and out of engagement with the rack 15. In other words, to effect a freeing of the shank 9 the parts are moved substantially to the position shown in Figure 3.

To accommodate the pin 16 and to permit disengagement of the pin 16 and rack 15 the sleeve 10 is provided internally thereof with a transverse recess or groove 25 as best shown in Figures 3 and 4.

Referring again to the thumb slide 24 it will be seen that the same is slidably accommodated at the junction of the handle 7 and shank 6 through the medium of a guide rib 26 formed integral with said handle 7 and shank 6; the guide rib 26 being accommodated by a groove 27

formed in one edge of the thumb slide 24 and complementing the rib 26.

Also on one edge or face thereof the slide 24 is provided with a recess 28 to accommodate the tip of the thumb to facilitate sliding the member 24 into and out of the positions shown respectively in Figures 3 and 4.

It is thought that the simplicity of a wrench embodying the features of the present invention, together with the many advantages of such a wrench will be clear to those skilled in the art without further detailed description.

It is also to be understood that while I have herein illustrated and described the preferred embodiment of the invention, I claim all such forms of the invention to which I am entitled and as fall within the scope of the appended claims.

Having thus described the invention what is claimed as new is:

1. In a wrench of the character described, a shank provided with a jaw at one end, a jaw complementing the first-named jaw and having an integrally formed shank, a sleeve pivoted adjacent one end thereof to the shank of the first-named jaw and embracing the shank of the second-named jaw; means mounted within said sleeve and engageable with the shank of the second-named jaw for securing the jaws at the desired relative position of adjustment; said means including a spring-biased element having an end projecting outwardly of said sleeve for engagement with the shank of the first-named jaw incidental to a biasing of said sleeve towards the first-mentioned jaw to effect a release of the shank of the second-named jaw; and interengaging means on the shank of the first-named

jaw and on said sleeve for arresting movement of the sleeve on its pivot towards the first-named jaw whereby to prevent accidental releasing of the second-named jaw.

5 2. In a wrench of the character described, a shank equipped at one end with a jaw and at a relatively opposite end with a handle, a jaw complementing the first jaw and provided with a shank, a sleeve pivoted adjacent one end thereof to the first-named shank and embracing the shank of the second-named jaw, the shank of the second-named jaw having rack teeth on one longitudinal edge thereof, oppositely disposed carrier members slidably mounted in said sleeve, 10 a locking pin connecting said members together and coacting with the teeth on said shank for securing the jaws at the desired position of adjustment, said sleeve provided with openings through which said carrier members project, 15 spring means operatively connected to the carrier members and normally urging the latter to a projected position and said locking pin in engagement with the aforementioned teeth; said carrier members being adapted, upon swinging movement of the sleeve towards the first-named shank to abut said shank for effecting a shifting of said carrier members in opposition to said spring for releasing the shank of the second-named jaw, and a thumb slide 20 slidably mounted on the shank of the first-named jaw and coacting with said carrier members to limit movement of the sleeve in the direction of the first-named shank, as and for the purpose specified.

CHARLES E. SCHILLING.
